UNITED STATES PATENT OFFICE.

FRED HUME, OF ST. LOUIS, MISSOURI, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-TOE-IRONING MACHINE.

Application filed November 11, 1926. Serial No. 147,645.

This invention relates to machines for ironing the toes of shoes, and an object of the invention is to provide a machine for use in the manufacture of shoes, whereby the folded edges of the shoe parts may be smoothly pressed and adhesively united with greater ease, rapidity and less cost than by present practices.

Another object of the invention is to provide a machine for ironing, smoothing and pressing the in-folded lower edges of the shoe uppers to form smooth surfaces so that, when the shoe is completed by the attachment of the sole, no grooves, openings or interstices will remain in the folds. In the accomplishment of this result, provision is made for the adjustment of the machine for work upon shoes of different sizes.

Various other objects of the invention will appear from the following description, reference being made to the drawings, in which

Fig. 1 is a front elevation of my improved machine.

Fig. 2 is a side elevation.

Fig. 3 is a plan view.

Fig. 4 is a relatively enlarged view with parts in section of the devices for supporting the shoe for operation of the ironing device.

Fig. 5 is a rear elevation of the toe supporting elements with parts in section.

Fig. 6 is a plan view of the heated ironing element.

Fig. 7 is a detail view of the pivotal support for the ironing element.

Fig. 8 is an enlarged sectional view of an elastic operating connection for the ironing member.

The machine frame is of strong and rigid construction and, as shown, the legs 1 may be angle bars having their respective flanges connected by cross angle bars 2. Two of the cross angle bars 2 are connected by an intermediate angle bar 3, the horizontal flange of which constitutes a guide for parts of the machine. A table top 4 is attached to the upper series of cross bars 2.

The machine shown is designed and adapted for operation upon both shoes of pairs of shoes and comprises supports for the right and left shoes respectively. The support for each shoe comprises a body 5 having at its front end of a pair of spaced standards 6 and at its rear end a slot 7 from each side of which rises a flange 8, the inner edges of

which extend toward each other beyond the inner walls of the slot 7 so that the space between the inner edges of the flanges 8 is of narrower width than the width of the slot 7 (Fig. 5). A bolt 9 extends through the slot 7 and through a hole in the frame top 4 and with the nut 10 constitutes a clamp for securing and holding the part 5 in rigid position and permits the part 5 to be secured in selected adjustments as required to accommodate shoes of different sizes.

A block 11 has a pair of laterally projecting trunnions 12 seated in notches in the standards 6 and a gripper or friction block 13 (Fig. 4) in each of said notches presses upon the trunnion 12 therein. A spring plate 14 at each side of the block 12 seats upon the upwardly extended end of the corresponding block 13 and, by means of pressure applied thereto by screws 15, causes the block 13 to bear with the desired pressure upon the trunnion 12 in order to hold the block 11 in its selected adjustments. That is, the upper end of the block 11 may be swung forwardly or rearwardly to a desired adjustment and retained in such adjustment by pressure of the blocks 13 upon the trunnions 12, but will permit the block 11 to be forced from one adjustment to another. A spindle 16 is screwed in the upper end of each of the blocks 11 and the length of each of said spindles above the corresponding block 11 may be varied as required to accommodate the machine for work upon shoes of different sizes. That is, for work upon shoes of small sizes, the spindles 16 will be adjusted to extend a greater distance above the blocks 11 than for work upon shoes of large sizes. A gage or clamping nut 17 is threaded upon each of the spindles 16 and may be turned thereon to the position desired to obtain the desired adjustment of the spindle 16 and to prevent accidental turning of said spindle.

Fig. 2 shows the manner in which a shoe in the course of manufacture is mounted for operation of this machine. As there shown, the shoe 18 is on its last 19, the rear end of which has a hole for the reception of the upper end of the spindle 16. In position, the last 19 rests upon the upper part of the nut 17. The support of which the spindle 16 forms a part may, as stated, be swung forwardly or rearwardly as required by the size of the shoe upon which work is to be performed. By

this, it will be seen that the shoe is placed upon the support upside down, the toe extending rearwardly.

The support for the toe comprises a block 5 20 extending between said flanges 8 and having a depending flange 21. A clamping bolt 22 (Figs. 4 and 5) has its polygonal head fitting in the slot 7. Said bolt extends upwardly through the block 20 and is equipped with 10 a clamping nut or sleeve 23 having a handle 24, whereby the same may be tightened or loosened. Thus, by loosening the nut 23, the block 20 may be moved toward or away from the shoe supporting spindle 16 as required to 15 support the toes of small or large shoes. The nut 23 is tightened to secure the toe supporting block 20 in proper adjustment. The upper end of the toe supporting block 20 is provided with a head 25 which is appropriately 20 dished to receive and support the toes of shoes having lasts therein. In use, the head 25 is preferably covered with a piece of chamois 26 or other appropriate material to prevent damage to the shoe when the machine is operated.

Each iron 27 is supported by a vertically movable frame. Each frame comprises a pair of rods 28, a cross head 29 connecting said rods at their upper ends, and a cross 30 head 30 connecting the lower ends of said rods. The rods extend for sliding movements through the top 4 and the cross bars 3 are guided thereby. One of the irons 27 is supported by each frame by means of a hanger 31 having pivotal connection 32 with the structure of the iron so as to permit such movement of the iron as may be necessary for it to press with equal pressure across the entire portion of the shoe upon which it is intended to operate. Each iron is provided with an electric heater 33 of known construction connected with circuit wires 34 by which the current is supplied, the current being controlled by any desired switch connections 45 (not shown).

Each rod 28 is encircled by a coiled spring 35. These springs 35 have their lower ends bearing upon the cross bar 3 and their upper ends against collars 36 rigid on the rods 28, 50 and thereby serves to support the iron frames in their highest elevation and to raise such frames after each operation. Extent of upward movement of the iron frames by the springs 35 is limited by collars 37 on the rods 55 28 arranged to abut against the undersurface of the top 4.

Each iron frame has operating connections. As shown, the operating connection for each frame comprises a link 38 extending downwardly from connection with the lower cross head 30 to connection with the cylinder 39. Each cylinder 39 encloses a spring 40. A rod 41 extends into each cylinder 39 through the spring 40 therein. A pin 42 in connection 65 with the upper end of each of the rods 40

constitutes an abutment for the upper end of the spring 40 and extends through slots 43 in the cylinder 39, thus permitting expansion and contraction of the spring 40 within limits. The lower end of the rod 40 is connected with a treadle lever 44 having its rear end pivoted to a part of the frame and its front end provided with a foot piece 45 whereby the treadle lever may be depressed to operate the iron frame and press the heated iron 75 upon the shoe to iron out the creases and smooth the united parts including the adhesive material, so that, when the shoe is finished by attachment to a sole, there will be no openings between the parts of the shoe. 80 The front end of each of the treadle levers 44 operates within a guide 46 provided with latch teeth 47 for engagement with a part 48 on the lever 44 to hold the lever 44 down so long as desired. The lever 44 is capable of 85 sufficient lateral oscillation to effect engagement and disengagement thereof with respect to the latch teeth 47.

In operation, the shoe is applied as shown (Fig. 2) and as herein described with the 90 last upon the spindle 16 and the toe of the shoe resting upon the non-abrasive cover 26 in order to present the bottom of the shoe having the creased folded edges toward the iron 27. Then, the treadle 44 is operated 95 to press the iron with the desired degree of pressure against that part of the shoe presented for operation of the iron thereon with the result that the parts are smoothed and the adhesive substance is caused to form a 100 smooth surface so that, when the shoe is finished, the parts present smooth surfaces against each other. The machine is capable of easy and rapid operation and may be constructed economically. The construction and 105 relationship of the cooperative elements of the machine may be varied within equivalent limits without departure from the nature and principle of the invention.

What I claim and desire to secure by Letters Patent is:—

1. In a machine of the character described, the combination of a heated ironing member formed and arranged to engage the major portion of the bottom of a shoe, an element cooperative with a last in the shoe to support the heel portion of the shoe with the bottom of the shoe toward the ironing member, a device cooperative with the toe portion of the shoe to support the shoe in said position, and means for effecting relative movement heightwise of the shoe between the shoe and the ironing member for causing the ironing member to press against the bottom of the shoe.

2. A machine of the character described comprising an adjustable support, a device in connection with said support for engaging a last in a shoe to support the shoe in inverted position, a support for the toe of the 125

shoe, said supports being constructed and arranged to hold the shoe in a fixed position, means for adjusting one of said supports with respect to the other, a heated ironing member formed and arranged to cover the forepart of the shoe bottom, and means for pressing the heated ironing member against the bottom of the shoe.

3. A machine of the character described comprising a heel support engageable with the last in an inverted shoe to support the heel end of the shoe in inverted position, a support for the toe end of the shoe, means for holding said supports in selected cooperative relationships and in fixed position, a heated ironing member supported above the shoe, said ironing member having an area sufficient to cover the major portion of the shoe bottom, and means for pressing the heated ironing member against the upwardly exposed bottom side of the shoe.

4. A machine for operating upon the bottoms of lasted shoes to prepare them for the reception of outsoles having, in combination, means for holding a lasted shoe in fixed position, a presser member adapted to engage simultaneously all portions of the overlasted upper about the major portion of the periphery of the bottom of the shoe, means for heating the presser member, and means for causing relative movement of the presser member and the shoe holding means heightwise of the shoe to apply pressure to the overlasted upper to remove wrinkles therefrom and to form an even surface for the application of an outsole.

5. A machine for operating upon the bottoms of lasted shoes to prepare them for the reception of outsoles having, in combination, means for holding a lasted shoe in a fixed position, a presser member adapted to engage all portions of the overlasted upper about the periphery of the bottom of the forepart of the shoe, means for heating the presser member, and means for causing relative movement of the presser member and the shoe holding means heightwise of the shoe to effect the removal of wrinkles from the overlasted portion of the upper and to form an even surface for the application of an outsole.

6. A machine for operating upon the bottom of a lasted shoe to prepare the shoe for the reception of an outsole having, in combination, means for sustaining the lasted shoe bottom up in a fixed position, a presser member adapted to engage the overlasted margin of the upper about the major portion of the periphery of the shoe bottom, means for heating the presser member, and means for moving the presser member perpendicularly to the shoe bottom to apply pressure to the overlasted margin of the upper and remove therefrom any wrinkles incident to the lasting operation to form an even surface for the application of the outsole.

7. A machine of the character described having, in combination, a shoe support comprising a heel pin and a toe rest arranged to present a shoe bottom up, a presser member constructed and arranged to cover the major portion of the bottom of the shoe, electric heating means enclosed in said presser member, and means for effecting relative movement of the shoe support and presser member heightwise of the shoe to press the shoe bottom.

8. A machine of the character described comprising means cooperating with a last in a shoe to support the shoe in inverted position, a support for the toe portion of the shoe cooperating with said means to support the shoe rigidly in fixed position, a heated ironing member adapted to engage simultaneously all portions of the overlasted upper about the periphery of the bottom of the forepart of the shoe, supports for supporting the heated ironing member above the shoe, means for actuating said supports to press the heated ironing member against the upwardly exposed bottom of the shoe, means for moving the heated ironing member away from the shoe, and means for limiting the extent of movement of the heated ironing member away from the shoe.

9. In a machine of the class described, the combination of a toe rest, a heel pin, a cross-head extending transversely of the forepart of the shoe located upon said heel pin and toe rest, an ironing member supported on said cross-head, a treadle connected to said cross-head for operating the ironing member, means for holding the ironing member in pressing relation against the forepart of the shoe bottom, and means for raising the cross-head when the ironing member is released.

10. A machine of the class described having, in combination, a shoe support comprising a heel support and a toe rest arranged to present a shoe bottom up, said heel support being adjustable relatively to the toe rest to vary the longitudinal inclination of the shoe bottom, a presser member constructed and arranged to tip laterally of the shoe to equalize its pressure at the two sides of the shoe, heating means for said presser member, and means for effecting relative movement of the shoe support and presser member heightwise of the shoe to press the shoe bottom.

11. A machine of the character described having, in combination, a shoe support having a heel pin and a toe rest arranged to present a shoe bottom up, a presser member constructed and arranged to tip laterally of the shoe, heating means for said presser member, and means for effecting relative movement of the shoe support and presser member heightwise of the shoe to press the shoe bottom, said pressure being equalized at the two sides of the shoe by reason of the tipping movement of the presser member.

12. A machine of the class described having, in combination, a toe rest, a heel pin, a cross-head extending transversely of the forepart of a shoe located upon said heel pin and toe rest, an ironing member supported on said cross-head, a treadle, a yielding connection between the treadle and said cross-head for operating the ironing member, means for holding the ironing member in pressing relation against the forepart of the shoe bottom, and springs for returning the cross-head to normal position.

13. A machine of the class described having, in combination, a toe rest, a heel pin hav-

ing laterally extending trunnions, friction blocks engaging said trunnions for maintaining said pin in adjusted position, an abutment vertically adjustable on said pin to vary the location of the heel end of the last with respect to the toe rest, a cross-head extending transversely of the forepart of a shoe located upon said heel pin and toe rest, an ironing member supported on said cross-head, a treadle connected to said cross-head for operating the ironing member, and means for holding the ironing member in pressing relation against the forepart of the shoe bottom.

FRED HUME.
